US0D1045965S

(12) **United States Design Patent** (10) **Patent No.:** **US D1,045,965 S**
(45) **Date of Patent:** **** Oct. 8, 2024**

(54) **EYEWEAR**

(71) Applicant: **Gentex Corporation**, Zeeland, MI (US)

(72) Inventors: **Mark R. Roth**, Grand Rapids, MI (US); **Yuhang Yang**, Comstock Park, MI (US); **Jason D. Hallack**, Holland, MI (US); **Sonali Agrawal**, Byron Center, MI (US); **Stephen M. Vruggink**, Zeeland, MI (US); **Justin D. Jansen**, Hudsonville, MI (US); **Andrew D. Weller**, Holland, MI (US); **Christopher A. Peterson**, Zeeland, MI (US); **Kevin A. Schueler**, Grand Haven, MI (US)

(73) Assignee: **GENTEX CORPORATION**, Zeeland, MI (US)

(**) Term: **15 Years**

(21) Appl. No.: **29/822,093**

(22) Filed: **Jan. 5, 2022**

(51) LOC (14) Cl. **16-06**

(52) U.S. Cl.

USPC **D16/309**
